US0D1001490S

(12) United States Design Patent (10) Patent No.: US D1,001,490 S
(45) Date of Patent: * Oct. 17, 2023

(54) BAG

(71) Applicant: CARTIER INTERNATIONAL AG,
Steinhausen (CH)

(72) Inventor: Jana Schlegel, Paris (FR)

() Term: 15 Years

(21) Appl. No.: 35/514,434

(22) Filed: Dec. 14, 2021

(80) Hague Agreement Data

Int. Filing Date: Dec. 14, 2021

Int. Reg. No.: DM/218031

Int. Reg. Date: Dec. 14, 2021

Int. Reg. Pub. Date: Jun. 17, 2022

(30) Foreign Application Priority Data

Jun. 18, 2021 (WO) WIPO105976

CLAIM

The ornamental design for a bag, as shown and described.

DESCRIPTION

Fig. 1.1 is a perspective showing my new design;
Fig. 1.2 is a front view thereof; and
Fig. 1.3 is a back view thereof.
Fig. 1.4 is a right view thereof.
Fig. 1.5 is a left view thereof.
Fig. 1.6 is a top view thereof.
Fig. 1.7 is a bottom view thereof.
The broken lines show portions of the bag that form no part of the design and are not claimed.

1 Claim, 7 Drawing Sheets
